UNITED STATES PATENT OFFICE.

JOHN C. WILSON, OF BOSTON, MASSACHUSETTS.

ELECTRICAL APPARATUS FOR AUTOMATIC SIGNALING.

SPECIFICATION forming part of Letters Patent No. 279,065, dated June 5, 1883.

Application filed January 16, 1882 (No model.)

To all whom it may concern:

Be it known that I, JOHN C. WILSON, of Boston, county of Suffolk, and State of Massachusetts, have invented an Improvement in 5 Apparatus for Automatic Signaling, of which the following description, in connection with the accompanying drawings, is a specification.

My invention relates to a system of signaling by automatic apparatus—such as may be 10 employed in an exchange for sending express-orders or for district-telegraph purposes when it is desired to send a large number of different messages, the object being to provide a signaling apparatus for sending any number 15 of different predetermined signals to a central station where a permanent record will be made.

For this purpose I employ a transmitting apparatus consisting of a motor for actuating a circuit-controlling device, independent of or 20 removable from the said motor, there being as many different circuit-controlling devices as there are signals to be sent. The said circuit-controlling devices are shown in this instance as perforated strips, which may be made to produce 25 any given signal in the Morse or other system, such signal usually consisting of a number by which the station from which it is sent is identified, followed by an abbreviated message indicating what is desired at the said station—such, for instance, as the name of the 30 express that it is desired to have called. These messages will be received upon a self-starting register, and can consequently be preserved for further reference, if need be. Each subscriber will be provided with any desired number 35 of the removable circuit-controlling devices or signaling-strips, which will be marked so as to enable him to readily identify them.

In addition to the mechanism by which the 40 strip is caused to make and break the circuit for the purpose of sending a signal, I employ a tap-bell and a switch which controls a shunt for the said bell and circuit-breaking apparatus, the said shunt being controlled by a device which in its normal position closes the 45 shunt and at the same time prevents access to the starting-knob for the automatic mechanism. When it is desired to send a signal the operator first moves the said device, causing it to 50 open the shunt and at the same time render the starting-knob accessible. By thus opening the shunt the tap-bell is brought into cir-

cuit, and will immediately indicate whether any other box in the same circuit is being operated or not. If the bell remains silent, the 55 operator will know that he can send a signal, and, having placed the desired signaling-strip in the box, he will start the mechanism which moves it along, it operating by its perforations to make and break the circuit in the well-known manner, and the tap-bell will respond, thus showing that the signal is being properly transmitted. If desired, a vibrating circuit-breaker may be employed at the central station, it being placed in circuit by the operator 65 after a signal has been properly received, and producing a vibration in the tap-bell, which will inform the subscriber of the fact that his message is received.

I am aware that permanent strips having a 70 series of parallel lines of perforations have been previously employed in connection with feeding mechanism and circuit-closers for the purpose of operating a musical instrument automatically, each key of the said musical instrument being controlled by the circuit-closer operated by one line of the said perforations, and I do not broadly claim a mechanically-fed permanent perforated strip in combination with an electric circuit controlled by it. 75

Figure 1 represents a signal-box adapted for 80 operation in accordance with this invention, the door being shown as open; Fig. 2, an enlarged section thereof, showing a portion of the perforated strip and circuit-breaker; Fig. 3, a detail of the starting-knob; Fig. 4, a view of one of the permanent signaling-strips, and Fig. 5 a diagram showing the electric circuit and apparatus therein.

Each subscriber is provided with a number 90 of circuit-controlling devices, shown in this instance as perforated strips *a*, (see Figs. 2 and 4,) adapted to give all the signals that he will desire, the said circuit-controlling devices being permanent and removable from or independent of the box or motor by which they are caused to effect the circuit. 95

The signal-box is provided with a hopper or guide tube, *b*, by which a strip is introduced between the feed-rolls *e d*, which are operated 100 by a train of wheel-work (shown in dotted lines Fig. 1,) in any usual manner, the said train being actuated by a weight or spring and governed by a fly or escapement in any usual man-

ner. One of the wheels *e* of the said train is provided with a projection, *f*, (see Fig. 3,) which, by its engagement with a stopping device, *g*, arrests the movement of the train.

5 The stopping device *g* is provided with a knob, *g'*, placed beneath an opening (shown in dotted lines at *h* in Fig. 1) in the door of a box, which is commonly kept closed, and by depressing the said knob *g'* the projection *f* is disengaged, and the train of wheel-work set in motion to carry the strip *a* through with a uniform movement.

A circuit-breaking lever, *i*, pivoted at 2, is provided at one end with a contact-point, *i'*, and at its other end with an adjustable finger, *i''*, that rests upon the strips *a* or drops through a perforation thereof, thus vibrating the said lever as the strip passes beneath it, and making and breaking contact of the point *i'* with 20 its anvil-piece or stop *j*.

The circuit or line *L* enters the box at the binding-screw 12, from which it is continued by wire 13 to the anvil-piece *j*, and thence it passes to the lever *i* when in its normal position, as shown in Fig. 2, the said lever being connected by wire 14 with the frame-work of the machine, which is connected by wire 15 with the coils of the audible signal or tap-bell *T*, from which the circuit is continued by wire 30 16 to the binding-screw 17 and line leading to the next station.

A spring, *k*, connected with the binding-screw 17 extends toward the contact-point *m*, connected with the binding-screw 12, so that 35 when the said spring is pressed against the said point the circuit is continued directly from the screw 12 to the screw 17, thus short-circuiting the breaking-lever *i* and tap-bell *T*.

The lever *n*, pivoted at 20, is provided with 40 a finger-piece, *n'*, extending outside the case in position to be engaged by the finger of the operator. The other end of the lever, when in the position shown in full lines, Fig. 1, being held by a spring, *n''*, covers the opening 45 *h*, through which access is obtained to the starting-knob *g'* of the train of wheel-work.

The bar *o*, connected with the lever *n*, engages (when the door of the box is closed) the spring *k*, and presses it against the contact-point *i* when the lever *n* is in its normal position covering the hole *h*. When, however, the operator desires to start the box and depress the lever *n* to uncover the hole *h*, the rod *o* is moved downward, and permits the 55 spring *h* to separate from the contact-point *m*, thus throwing the circuit-breaking lever *i* and tap-bell *T* into the circuit.

If another box should happen to be in operation, the tap-bell would immediately give 60 response, so that the operator would be warned not to start his box; but if the tap-bell was silent he would know that it was proper for him to press the knob *g'* and send his signal.

The signals are received on a self-starting 65 register, *R*, (see Fig. 5,) of usual construction, and, if desired, an automatic circuit-breaker—such, for example, as an ordinary

vibrating bell, *S*—will be employed at the central office, and will be introduced into the circuit—as, by depressing the key *K*, and thus 70 opening a normally-closed shunt for the said vibrator—immediately after a signal has been received, it setting the tap-bell in operation and producing a signal different from that made by the breaking-lever *i*. 75

The strips *a*, preferably made of sheet metal, are of such thickness as to raise the lever *i* sufficiently to break the circuit at *i''j* when the finger *i''* rests on the said strip, which will be stamped with the signal it is intended to 80 convey, as shown.

The strip shown in Fig. 4 is perforated to give the Morse signal "144 Am.," which is to indicate that the "American" express is desired to call at station 144. The strip is provided at its end which enters the feed-tube *b* with a slot, 23, to permit its end to reach and be engaged by the feed-rolls before the break-lever is affected by it.

I am aware that the receiving apparatus of 90 a district-telegraph system has been provided with a circuit-breaker for causing an answer-back signal at the box from which a message has been received, and I do not broadly claim means for producing an answer-back signal. 95

I claim—

1. In a district-telegraph system or exchange the following elements, namely: a signal-box or motor, independent removable circuit-controlling devices adapted to be operated by the 100 said motor, and receiving apparatus for the signals thus sent, all co-operating as described, whereby an unlimited number of different messages may be sent, substantially as described.

2. The combination, with the perforated 105 strips and feed-rolls, and actuating mechanism therefor, of a circuit-breaking lever, and signal-instrument in circuit therewith, a shunt-circuit therefor and circuit-closer therein, a starting-knob for the said actuating mechanism, and device for simultaneously controlling the said shunt-circuit closer and access to the said starting-knob, substantially as and for the purpose described.

3. In a district-telegraph system or exchange, the main circuit and signal boxes or transmitting apparatus therein provided with audible signals, receiving apparatus in the said main circuit at the main or central station, and the vibrating circuit-breaker in a 120 branch of the main circuit at the central station, and a key for throwing it into the main circuit, whereby the audible signal may be operated at the transmitting-box when desired for indicating that a message has been 125 received at the central station, substantially as set forth.

In testimony whereof I have signed my name to this specification in the presence of two subscribing witnesses.

JOHN C. WILSON.
